(57) **CLAIM**

The ornamental design for a stackable friction clutch coil for torque distribution system, as shown and described.

DESCRIPTION

FIG. 1 is a right view of my design for a stackable friction clutch coil for torque distribution system.

FIG. 2 is a left view thereof.

FIG. 3 is a top planar view thereof.

FIG. 4 is a right top front perspective view thereof.

FIG. 5 is a front view thereof.

FIG. 6 is a rear view thereof.

FIG. 7 is a bottom view thereof.

FIG. 8 is a rear right top perspective view thereof; and,

FIG. 9 is rear left top perspective view with thereof.
